FIGURE 2 is a perspective view showing the front, top and other side of this machine in closed position with its microphone and control portion forming the top of the machine and with the handle portion positioned above it;

The dominant features of my design reside in the portions shown in the full lines in the drawings.

I claim:

The ornamental design for a portable dictating machine, substantially as shown and described.
